(57) **CLAIM**

The ornamental design for a corner masonry block, as shown and described.

DESCRIPTION

FIG. 1 is a perspective view of a first embodiment of a corner masonry block showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right-side elevational view thereof;

FIG. 7 is a left-side elevational view thereof;

FIG. 8 is a perspective view of a second embodiment of the corner masonry block showing my new design, the difference being the mating surfaces for mating between two corner masonry blocks is reversed;

FIG. 9 is a top plan view thereof;

FIG. 10 is a bottom plan view thereof;

FIG. 11 is a front elevation view thereof;

FIG. 12 is a rear elevation view thereof;

FIG. 13 is a right-side elevational view thereof;

FIG. 14 is a left-side elevational view thereof;

FIG. 15 is a perspective view of a third embodiment of the corner masonry block showing my new design, the difference being that the orifice is part of this claimed design;

FIG. 16 is a top plan view thereof;

FIG. 17 is a bottom plan view thereof;

FIG. 18 is a front elevation view thereof;

FIG. 19 is a rear elevation view thereof;

FIG. 20 is a right-side elevational view thereof;

FIG. 21 is a left-side elevational view thereof;

FIG. 22 is a perspective view of a fourth embodiment of the corner masonry block showing my new design, the difference being the mating surfaces for mating between two corner masonry blocks is reversed;

FIG. 23 is a top plan view thereof;

FIG. 24 is a bottom plan view thereof;

FIG. 25 is a front elevation view thereof;

FIG. 26 is a rear elevation view thereof;

(Continued)

FIG. 27 is a right-side elevational view thereof; and, FIG. 28 is a left-side elevational view thereof. The dash-dash broken lines depict portions of the corner masonry block that form no part of the claim. The dash-dash broken lines act as boundaries of the claim where they intersect claimed surfaces. The dash-dot lines are score lines and are not part of the claimed design.
